UNITED STATES PATENT OFFICE.

CHARLES E. BENTLEY, OF NEW YORK, N. Y.

DESIGN FOR A BOTTLE.

SPECIFICATION forming part of Design No. 20,030, dated July 15, 1890.

Application filed June 3, 1890. Serial No. 354,141. Term of patent 7 years.

To all whom it may concern:

Be it known that I, CHARLES E. BENTLEY, a citizen of the United States, residing at the city of New York, county and State of New York, have invented and produced a new and original Design for a Bottle, of which the following is a specification, reference being had to the accompanying drawings, forming part thereof.

10 Figure 1 is a side view of a bottle as seen from one corner of its body portion and embodying my design; and Fig. 2 is a plan view thereof, these two views being deemed necessary to fully illustrate the design.

15 The leading features of novelty of my design for a bottle or dressing-case ornament consist, more particularly, in the configuration of its lower body portion, which is surmounted by a comparatively long central 20 neck or stem.

The body A of the bottle or ornament, as viewed from the side in the position shown in Fig. 1 of the drawings, is surmounted by a central neck or stem a, which is preferably 25 slightly enlarged toward the top, but may be straight or cylindrical from end to end. From the base or root of the neck or stem the body A of the bottle presents the general appearance of having been turned in a lathe and 30 then cut off vertically at four sides to form

four flat rectangularly-disposed substantially plane faces. The comparatively straight upper face or portion 1 of the body A slopes or inclines downwardly and merges into a rounded side or edge outline 2, which merges into 35 a downwardly and inwardly curved lower part 3, which dies away at the bottom or base line 4 of the bottle.

Fig. 2 of the drawings shows that the four flat vertically-ranging and right-angularly-disposed side faces 5 5 5 5 do not meet at their ends, thereby leaving or producing what may be termed "corners" 6 6 6 6, which are curved vertically on the edge line 2 of the sides of the body, and are curved horizontally on a 45 line struck from the center of the body. The vertically-curved side outlines of the body A cause its four flat faces 5 to present a substantially oval marginal outline to the eye, as seen best in Fig. 1 of the drawings. 5c

An ordinary cut-glass stopper is shown in the neck of the bottle.

I claim as my invention—

The design for a bottle, substantially as herein shown and described.

CHARLES E. BENTLEY.
